INVENTOR

WITNESS: .

UNITED STATES PATENT OFFICE.

FRANK P. DYER, OF ST. LOUIS, MISSOURI.

TRESTLE.

Application filed February 7, 1927. Serial No. 166,561.

This invention relates to trestles and its primary object is to provide a trestle of the foldable and knock-down type, for use by mechanics such as carpenters, paper hangers, and the like, that can be expeditiously set up to provide a strong, sturdy and substantial supporting structure of any size and height within the limits of the structure, and can be easily and quickly reduced when not in use to occupy minimum space in storage and to render the same easily transportable in great numbers.

This invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:

Figure 1 is a perspective view of the trestle forming the subject matter of the present invention and showing the same assembled.

Figure 2 is a fragmentary side elevation and illustrating the supporting legs and brace means therefor.

Figure 3 is a sectional view taken on line 3—3 of Figure 2.

Figure 4 is a detail view showing an example for one of the legs.

Referring to the drawings in detail the standards or legs are arranged in cooperating pairs and each pair includes uprights 1 and 2 pivotally secured for cooperation adjacent the upper ends by spaced parallel strips 3. Cross braces 4 are also provided for the uprights and these braces are longitudinally slotted as at 5 to receive bolts 6 having thumb nuts 7 associated therewith as best shown in Figure 1 of the drawings.

The upper ends of the uprights 1 and 2 are recessed as at 8 for providing shoulders 9 and to accommodate the cross beam 10 which may be of various sizes and lengths and yet be adequately and substantially supported by the standards as will be readily apparent. Converging brace rods are provided for the cross beam 10 and include angle bent lower ends 11 having openings 12

adapted to receive the bolts 6 as clearly shown in Figure 2 of the drawings. The converging rods have bent tapered upper ends providing penetrating points adapted to be embedded in the beams in the manner as best shown in Figure 2, and thereby adequately support the central portion of the beam as will be readily apparent.

I have also provided sleeves 13 adapted to telescopically receive the uprights 1 and 2 and these sleeves have arranged therein thumb bolts 14 whereby they can be adjusted on the uprights 1 and 2 to also change the height of the trestle as desired.

From the above description and disclosure of the drawings, it will be obvious that I have provided a trestle formed with legs which include uprights mounted for adjustment with respect to each other so that the space between the recessed ends can be varied to accommodate beams 10 of various widths and which also will enable the trestle to be adjusted to various heights by the movement of the legs toward and away from each other.

It is thought from the foregoing description that the advantages and novel features of my invention will be readily apparent.

I desire it to be understood that I may make changes in the construction and in the combination and arrangement of the several parts, provided that such changes fall within the scope of the appended claim.

What I claim is:

A trestle of the character described comprising a pair of upwardly converging legs spaced at their upper ends, a pair of spaced oppositely disposed cross members pivotally connected to said legs adjacent their upper ends, a cross beam received between said upper ends and supported by said cross members, a longitudinally slotted cross member and bolts and wing nuts for adjustably connecting said slotted cross member to said legs at intermediate points of said legs, said bolts being slidably extended through said slot, brace members pivotally connected to said legs by said bolts and converging upwardly toward the center of said cross beam, said brace members having penetrating points formed thereon and arranged at angles thereto and embedded in said cross beam substantially as described.

In testimony whereof I affix my signature.

FRANK P. DYER.
